UNITED STATES PATENT OFFICE.

ALBERT MARKS, OF SPRING LAKE, WISCONSIN, ASSIGNOR TO EDWARD H. HEATH, OF MADISON, WISCONSIN.

PORTABLE FILTERING DEVICE.

SPECIFICATION forming part of Letters Patent No. 634,470, dated October 10, 1899.

Application filed May 10, 1899. Serial No. 716,273. (No model.)

To all whom it may concern:

Be it known that I, ALBERT MARKS, a citizen of the United States, residing at Spring Lake, in the county of Waushara and State 5 of Wisconsin, have invented certain new and useful Improvements in Portable Filtering Devices, of which the following is a specification.

My present invention pertains to improvements in portable filtering devices, the construction and advantages of which will be hereinafter set forth, reference being had to the annexed drawings, wherein—

Figure 1 is a side elevation of the complete apparatus; Fig. 2, a vertical sectional view of the filtering-chamber, and Fig. 3 a top plan view of the same.

In the use of traction-engines and the like the question of a suitable water-supply is one 10 which frequently gives no little trouble, for, as is usually the case with such engines, the supply must be drawn from creeks and streams more or less contaminated with mud, sand, and other extraneous matter. The introduction 15 of these substances into the working parts of the engine through the feed-water pipe is frequently a matter of serious consequence.

Again, traction-engines often haul their own tank along with them or have the feed- 20 tank mounted on the frame or running-gear of the engine, and in passing up or down an incline when the water is low in the tank the supply-pipe or opening thereto is frequently uncovered, allowing air to be drawn into the 25 engine instead of water. This also at times is a serious drawback.

The object of my present invention is to overcome both of these difficulties and to insure 30 a clean-water supply and at the same time a constant one, notwithstanding that the volume of water in the tank below and the apparatus is passing over an uneven country.

Referring to the drawings, A indicates the body of the tank, which in the present instance is shown as mounted upon an ordinary vehicle running-gear, said tank or receptacle 45 having an opening B, formed in the bottom thereof, as shown in dotted lines in Fig. 1 and in full lines in Fig. 2. Said opening is preferably formed near the center of the tank, for a purpose that will presently appear. Se-

cured to the under face of the tank is a filtering-chamber or trap C, the location of the chamber being such that the opening B is in communication therewith. This filtering-chamber is preferably formed with a downwardly-inclined face or bottom D, provided at its lowest point with a draw-off which is closed by a plug E. To provide for the filtration of any water which passes through the trap or filtering-chamber C, I employ a screen F, which may be of any suitable substance or material capable of straining the water and yet at the same time permitting a sufficient flow therethrough. The material used 65 may be canvas, finely-woven wire, a medium of baked clay, or the like.

Referring more particularly to Fig. 2, it will be noted that the screen F is placed in an inclined position, so that any water which 70 passes through the same will move in an upward direction.

G denotes the outlet, which in practice is connected by a suitable hose or pipe to the injector or pump of the engine. This outlet 75 is placed upon the opposite side of the screen F from the opening G, so that any and all of the water which is drawn out through said outlet G must of necessity pass through the filtering screen or medium. In so doing it 80 will be cleansed of those matters which it is desirable to exclude from the working parts of the pump or engine.

By reason of the inclined position of the filtering screen or medium the dirt which will 85 accumulate on the under side or face thereof will have a tendency to fall to the bottom of the filtering-chamber or trap, and said screen or filtering medium may be readily and easily cleansed by reversing the flow of liquid there- 90 through.

Any accumulation of mud, sediment, or the like can be withdrawn from the trap or filtering-chamber from time to time by the removal of the plug E.

As will be noted upon reference to Fig. 1, the tank is shown as containing but little water and also being in an inclined position. It will, however, be observed that the water contained therein covers the opening B, leading to the filtering-chamber or trap, and by locating the opening centrally with reference

to the bottom of the tank the water will at all times or practically so cover said opening and prevent the drawing in of air through the same. Of course when the bottom of the tank is in a horizontal position the water therein will naturally cover the opening as long as there is any liquid left in the tank.

The invention is susceptible of various modifications in its detail, especially with reference to the formation and construction of the filtering-chamber or trap. So, too, the idea is applicable, as above stated, to tanks or reservoirs which are carried directly upon or by the engine, and the form shown in Fig. 1 is to be taken simply for the purpose of illustration.

By having the filtering-chamber or trap in communication with the tank through a small or restricted opening the water which enters the filtering-chamber or trap will be held therein against displacement by a momentary tilting of the body of the tank. This is important where but a small quantity of water is held by the tank, and the opening 25 B will be uncovered and air be free to enter therethrough. The restricted opening also prevents to a certain degree the mud or other material which will accumulate upon the bottom of the tank from entering the filtering-chamber, except that which is directly around it or passes directly over it as the water may move back from one end of the tank to the other.

Having thus described my invention, what 35 I claim is—

1. In combination with a tank; a filtering-chamber or trap secured to the under side thereof; an opening extending from said tank into the filtering-chamber; a filtering medium mounted within said trap, to one side of the opening; and an outlet in said trap upon the opposite side of the filtering medium.
2. In combination with a portable tank having an opening in its base; a filtering-chamber in communication with said opening; a filtering medium mounted within said chamber, to one side of the opening in the tank; and an outlet for said filtering-chamber, ar-

ranged upon the opposite side of said filtering medium, substantially as described.

3. A portable filter comprising a suitable tank or receptacle provided with a discharge-opening formed near the center of its base; a filtering-chamber or trap in communication with said opening; an opening leading from the trap; and a filtering medium interposed between said openings, substantially as described.

4. A portable filter comprising a suitable tank or receptacle having an opening formed centrally in its base; a filtering-chamber or trap secured to said tank and in communication with the opening, said chamber being formed with an inclined face or bottom D; a draw-off opening formed at the lower end of said inclined face; an outlet G; and a filtering medium extending across the filtering-chamber or trap, intermediate the opening G and the central opening in the base of the tank.

5. In a portable filter, the combination of a suitable tank or receptacle provided with a central opening in its base; a filtering-chamber or trap secured to said base and in communication with the opening therein, said chamber or trap being formed with a downwardly-inclined face D; a draw-off opening formed at the lower end of said inclined face; an outlet-opening G; and an inclined filtering medium secured within the trap, intermediate the opening G and the opening in the base of the tank.

6. In a portable filter, the combination of an unfiltered water receptacle; a filtering-chamber or trap connected directly to the bottom thereof by a restricted opening; a filtering medium supported within said trap; and an outlet for the filtered water leading from the trap.

In witness whereof I hereunto set my hand 90 in the presence of two witnesses.

ALBERT MARKS.
